FINGER RING

Frank P. Ciambra, 772 Stewart St., and Herman Noriega,
760 Stewart St., both of Ridgefield, N.J. 07657

Filed Sept. 29, 1972, Ser. No. 297,399

Term of patent 14 years

Int. Cl. D11—01

U.S. Cl. D45—10 C

Fig. 1

Fig. 4

FIG. 1 is a top plan view of a finger ring showing our new design.

FIG. 2 is a side elevational view as seen from the left of FIG. 1.

FIG. 3 is a side elevational view as seen from the right of FIG. 1.

FIG. 4 is a front elevational view as seen from below FIG. 1, the view from the rear presenting a substantially identical appearance.

FIG. 5 is a bottom plan view.

FIG. 6 is a top perspective view thereof on reduced scale as it appears in open position.

We claim:

The ornamental design for a finger ring, substantially as shown and described,
